(57) **CLAIM**

The ornamental design for a binding tool, as shown and described.

DESCRIPTION

FIG. 1 is a perspective view of the front, top and left side of a binding tool showing my new design;

FIG. 2 is a perspective view of the rear, top and right side thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines depict portions of the binding tool that form no part of the claim.

1 Claim, 6 Drawing Sheets
